UNITED STATES PATENT OFFICE.

EARL G. FIDLER, OF GARRETT, PENNSYLVANIA.

RAIL-JOINT.

1,234,321.

Specification of Letters Patent. Patented July 24, 1917.

Application filed April 1, 1916. Serial No. 88,369.

To all whom it may concern:

Be it known that I, EARL G. FIDLER, a citizen of the United States, residing at Garrett, in the county of Somerset and State of Pennsylvania, have invented certain new and useful Improvements in Rail-Joints, of which the following is a specification.

This invention relates to rail joints, and has more special reference, to an improved boltless joint.

The primary object of the invention is to provide a joint of the character described, whereby, the rail engaging chairs are so supported, as to, when moved in opposite relative directions, automatically clamp and secure the adjoining ends of the rail sections.

Another important characteristic of the invention, resides in the provision of novel means, whereby, further movement of the rail chairs, when moved into a clamping position, will be positively prevented.

It is also among the aims and objects of this invention, to provide a rail joint, which will be of exceedingly simple construction, the various constituent elements thereof, being closely assembled; one which is efficient for the purpose to which it is designed, and finally, strong and durable in use.

Other improvements and novel details in the construction and arrangement of the various parts of the apparatus, will be brought out more in detail in the description to follow, which, for a clear understanding of the invention, should be considered in connection with the accompanying drawings, forming a part thereof, and wherein is disclosed, for the purpose of illustration, convenient and satisfactory embodiments of the invention.

In the drawings:—

Figure 1 is a side elevation of my improved joint, as applied;

Fig. 2 is a top plan, partly in section;

Fig. 3 is a transverse section taken on the line 3—3 of Fig. 1;

Fig. 4 is a transverse section, taken on the line 4—4 of Fig. 1;

Fig. 5 is a detail of the supplemental clamping member; and

Fig. 6 is a detail in perspective of its complementary or coacting clamping member.

Referring now more particularly to the drawings, wherein like reference characters designate like or corresponding parts

throughout the several views thereof, it may be stated, that the adjoining rail sections are designated by the numerals 1 and 2, while the cross ties are indicated at 3, in general.

Referring now to the present improvements I provide complementary rail securing chairs 4 and 5, which are provided with vertically disposed bracing webs 6. The rail securing chair 4 is provided with a base portion 7, which has arranged therein, a diagonally extending way 8, it being noted that the outer extremity of the base portion 7, adjacent the way 8, is provided with a substantially tapered arm 9, the inner face of which is beveled as at 10, while, the opposite side of the way 8, formed by the base portion 7, is beveled as at 11. To provide for means whereby a portion of the rail 75 may be supported upon the base 7, I arrange thereupon a laterally extended portion 12, which portion is provided with, adjacent its outer extremity, a depending rib 13. The remaining rail securing chair 5, is so 80 constructed as to be received within the diagonally arranged way 8, as formed in the base portion 7 and comprises a base portion 14, having arranged upon its under face, a depending leg 15, the outer face of 85 which is beveled to conform to the portion 10, while the opposite side face has formed thereupon, a lateral extension 16 the said extension having arranged thereupon a vertically projecting rib 17, the outer face of 90 which is beveled to conform to the side or face 11 of the said portion 7. It will be noted that the rail chairs 4 and 5 extend slightly beyond their respective base portions, as indicated at 18 and 19, permitting 95 the same to rest upon the cross ties 3. Notches as generally indicated at 20, are arranged adjacent the edges of the said chairs, to permit the driving of spikes 21 into the cross ties, the heads of the spikes engaging 100 with the rail chairs and consequently, securely affixing the same to said cross ties.

In order to provide for means whereby further movement of the rail securing chairs will be prevented, when once the adjoining rail sections have been clamped therebetween, I arrange upon one end of the chair 4, an elongated support 22. Formed integrally with the outer extremity of this support, is a clamping element 23, which has 110 arranged adjacent its outer side, a hooked or rail engaging portion 24, while the inner

side thereof is reduced to provide a portion 25, which portion has arranged therein, a diagonally extending groove 26. To the forward end of the device, there is secured 5 an extending lug or stop 27, which stop is adapted to engage with the adjacent side of a cross tie 3. A complementary fastening member 28 having formed upon its outer side, a hooked or rail engaging portion 29 and a reduced part 30, so formed as to provide a diagonally extending engaging finger 31, which engaging finger is engaged with a diagonally extending groove 26 as arranged in the first mentioned clamping member 23. 10 The other rail chair 5 has formed upon the opposite end thereof, a similar elongated element 32, of less length than the elongated support 22, and, has arranged upon its outer extremity a clamping member constructed in 15 exact accordance with the clamping member 23, with the exception, that the stop 27, is omitted. A complementary clamping member is engageable with this second mentioned clamping member and is also constructed in 20 a similar manner as the clamping member 28. Hence, it is deemed, that the description of this second mentioned clamping member is unnecessary, since those numerals as applied to the first mentioned clamping 25 members may be similarly applied in this particular instance. Attention is directed to the fact that the inclined grooves 26 and the inclined fingers 31 of the clamping members 23 and 28 respectively are arranged so 30 as to extend in a direction opposite to the diagonal or inclined way 8, in the base portion 7.

In operation, the adjoining rail sections 1 and 2 are received by the rail chairs 4 and 40 5, the way 8 as arranged in the base portion 7, is accordingly engaged with the depending leg 15. Thus, when the base portions 7 and 14 are moved in relatively opposite directions, the rail chairs 4 and 5, will, due to the diagonally arranged way 8 and the similarly constructed depending leg portion 15, be moved laterally toward each other, consequently, firmly clamping the ends of said adjoining rail sections. It is to 45 be also noted that the clamping members 23 and 28, as arranged upon the elongated supporting member 22 are engaged with the base of one of the adjoining rail sections, namely, 2, while the clamping members as 50 arranged upon the elongated supporting member 32 are engaged with the base portion of the remaining adjoining section, namely, 1. The clamping members 23 and 28 and the similar clamping member 32 55 which are engaged with the abutting rail sections will, should relative movement of the said sections be permitted, clamp upon the base portions of the said rails. This clamping action is due to the arrangement 60 of the inclined ways and fingers, thus pre-

venting spreading of the rails which would otherwise be permitted especially in the event that the spike or other securing means should become worn or broken. The stop 27 as arranged upon the clamping element 23 70 will abut the near side of the adjacent tie 3, and consequently prevent further movement of the said element. Should for any reason, the spike 21, become broken or worn to such an extent as to permit a slight relative 75 movement of either of the rail chairs 4 and 5, the clamping members 23 and 28, due to the opposite arrangement of the grooves 26 and engaging fingers 31, will accordingly be moved toward each other, thereby, causing 80 the rail engaging portions 24 and 29 to bind the oppositely disposed portions of the rail base with which they are engaged.

It will be understood that the drawings 85 illustrate a preferred embodiment of the invention and that minor changes in this particular construction and arrangement of parts, may be made within the scope of the appended claims, without deviating from the nature or principle of my invention. 90

I claim:—

1. In a rail joint, including abutting rail receiving means, and clamping means carried by and arranged beyond the ends of said receiving means and engaged with the abutting rail sections, said clamping means being adapted to grip the rail base more tightly upon separation of the rails. 95

2. In a rail joint, rail receiving chairs, and wedge actuated clamping means arranged adjacent said chairs and engaged with the abutting rail sections for preventing relative movement of the same in said chairs. 100

3. In a rail joint, rail receiving chairs, 105 clamping means arranged adjacent said chairs and engaged with the abutting rail sections for preventing relative movement of the same in said chairs, and means arranged upon said clamping means for causing lateral movement of the clamping means when shifted longitudinally. 110

4. In a rail joint, rail receiving chairs, clamping members carried by and extending beyond the ends of said chairs and engaged 115 with the abutting rail sections for preventing relative movement thereof in said chairs, and means arranged upon the base portions of the clamping members for causing lateral movement thereof when shifted longitudinally. 120

5. In a rail joint, rail securing chairs, clamping means carried by and arranged beyond the ends of said chairs, said clamping means being engaged with the abutting rail sections, and means carried by one of the clamping means engageable with an object for limiting the movement thereof. 125

6. In a rail joint, rail securing chairs, clamping members carried by and extend- 130

ing beyond the ends of said chairs, said clamping members comprising interlocked slideable elements, and means arranged upon said slideable elements for causing lateral 5 movement thereof when shifted longitudinally.

7. In a rail joint, rail securing chairs, clamping members arranged at the ends of said chairs and engaged with the abutting 10 rail sections, said clamping members comprising slideable portions for diagonally arranged interconnected portions formed upon their adjacent ends whereby the same will be caused to move laterally upon longitudinal 15 movement of the interconnected portions.

8. A rail joint including rail clamping chairs adapted to receive and secure the abutting ends of the rail sections, interlocked base portions supporting said chairs, 20 one of said base portions being provided

with a diagonally arranged track-way adapted to receive said second mentioned base portion, whereby said rail chairs will be moved laterally upon relative longitudinal movement of said base portions, and clamping means arranged adjacent said clamping chairs for preventing further longitudinal movement of the same when moved to a clamping position, said clamping means comprising slideable hooked portions having diagonally arranged inter-connected portions formed upon their adjacent extremities whereby said hooked members will be moved laterally upon longitudinal movement of 35 said diagonally interconnected portions.

In testimony whereof I affix my signature in presence of two witnesses.

EARL G. FIDLER.
